(57) **CLAIM**

The ornamental design for a hair braid, as shown and described.

DESCRIPTION

FIG. 1 is a perspective view of a hair braid showing my new design;

FIG. 2 is a front elevation thereof;

FIG. 3 is a rear elevation thereof;

FIG. 4 is a left-side elevation thereof;

FIG. 5 is a right-side elevation thereof;

FIG. 6 is a top plan view thereof; and,

FIG. 7 is an enlarged bottom plan view thereof.

The dashed lines in the drawings are included for the purpose of illustration and form no part of the claimed design.
